LADY'S HANDBAG FRAME

Salvatore Giordano, Forest Hills, N. Y.

Application July 5, 1947, Serial No. 759,213

1 Claim. (Cl. 150—29)

1

This invention relates to improvements in handbags such as are popularly used for the holding of objects.

It is an object of my invention to provide a handbag with novel means for suspending a supplemental purse or container or other object therein in easily accessible fashion, without interfering with the continuous cross sectional outline of the frame members essential to the neat and complete bagging of the frame.

An embodiment of a structure employing my invention is shown in the accompanying drawings and described in detail in the ensuing specification. This embodiment is merely by way of example; my invention is not limited thereto but includes all other forms which would come within the scope of the appended claim. In the drawings.

Fig. 1 is a fragmentary, elevational view of a portion of a frame member embodying my invention.

Fig. 2 is a similar view, showing fragmentarily an object suspended from the frame member.

Fig. 3 is an enlarged sectional view, taken on line 3-3 of Fig. 1.

Fig. 4 is a fragmentary, perspective view, taken on line 4-4 of Fig. 2.

Fig. 5 is a perspective view of a bag frame provided with an object suspended therein pursuant to my invention.

Fig. 7 is a similar view, generally corresponding with that shown in Fig. 2 (but indicating the use of the form of invention in Fig. 6) for the suspending of an object from the frame.

The drawings illustrate the practical application of my invention to a bag frame consisting of the frame sections 10 and 11 which are pivoted together as at 12 at the ends of the leg members 16, 16' of said frame sections, each frame member being generally channeled in cross section (Fig. 3) and having inner and outer walls 14 and 13 defining an opening 15 substantially co-extensive with the frame sections and continuing to the free end points 18 of outer walls 14 immediately adjacent the pivot points 12. The bag material (not shown) is clamped marginally in the frame sections by passing the said material into said frame sections through the opening 15 and bending the wall 14' toward the wall 13, or by similar expedients well known to those skilled in this art.

Pursuant to my invention, the object 17 (such

as an inner purse) is suspended from the frame sections 10 and 11 at the point immediately adjacent the pivot 12 to permit of the full and unimpaired opening and closing of the frame sections in the usual fashion, and the full utilization of the inner wall 14 throughout its length—to the point 18—to clamp the bag material within the frame sections, in a manner essential to provide for the neat bagging of the material. In the form shown in Fig. 1, the plate 19 is cut from the inner wall 14 at a point spaced from the end point 18 of said inner wall 14, plate 19 being initially bent outwardly of the plane of the wall 14 (Fig. 3) defining therewith a guide whereby the straps 20 or other terminal securing means for the object 17 may be simply positioned under the plate 19 and over the wall 14, and then the plate 19 may be bent to a position substantially in the plane of the inner wall 14 (see Figs. 2 and 4) to effectively hold the strap 20 on wall 14. The bag frame thus completed with the object 17 suspended therefrom may subsequently be bagged as desired. It will be noted by the use of my invention, the object 17 may be secured to the frame sections 10 and 11 at one time, and the bagging of the frame may be completed at another time, if so desired. For example, it might be desirable to provide the frame with the object 17 as a standard unit to bag manufacturers who could then complete the bag by the use of material to be secured within the frame sections of the desired style and quality. It will be apparent that by the use of the invention, it is possible to utilize the full length of the inner wall 14 up to and including the end point 18 thereof adjacent the pivot, including also the plate 19, holding the bag material up to and including the point 18 firmly within the frame sections. Thus, there is presented a neat and finished appearance at the ends of the bag, to the same extent as would be the case wherein the conventional uninterrupted wall 14 were used.

In the form shown in Figs. 6 and 7, a plate 21 is welded or otherwise secured at one end 22 to the inner wall 14, the other, free end 23 of said plate being adapted to be doubled over and clinched upon the secured end 22 with the straps 20 of the object 17 thus clinched within the plate 21 (see Fig. 7).

50 Having thus described my invention, what I claim as new and desire to secure by Letters Patent is:

In a handbag frame having inner and outer walls defining a channel for the reception of bag material, a plate cut from the inner wall at a

point spaced from the end point of said inner wall, said plate being bent beyond the plane of the inner wall and being adapted to define therewith a guide for the reception of securing means for an object to be suspended from the frame, being adapted to be bent substantially into the plane of the inner wall to hold said securing means to the inner wall and providing an uninterrupted opening between the inner and outer walls for subsequent reception of the bag material therebetween.

10 SALVATORE GIORDANO.
